UNITED STATES PATENT OFFICE.

EMILE LAROCHE, OF ANGERS, FRANCE.

STOVE.

SPECIFICATION forming part of Letters Patent No. 595,952, dated December 21, 1897.

Application filed August 8, 1896, Serial No. 602,171. (No model.) Patented in Belgium April 27, 1896, No. 121,088, and in France June 10, 1896, No. 253,040.

To all whom it may concern:

Be it known that I, EMILE LAROCHE, of Angers, (Maine-et-Loire,) France, have invented certain new and useful Improvements in 5 Stoves, of which the following is a full, clear, and exact description.

This invention has been patented in France June 10, 1896, No. 253,040, and in Belgium April 27, 1896, No. 121,088.

10 My invention relates particularly to the means for regulating the draft in the stove.

The drawing shows a stove, in central vertical section, embodying my invention.

The body of the stove is shown at A, hav- 15 ing a fire-pot C and a fuel-door B.

a is a door leading into the ash-pit.

f is the smoke-outlet.

The air for the draft is led into the stove 20 by a draft-pipe F from the outer air. This pipe extends through the ash-pit and opens

into a box G. This box opens into the ash-pit just below the grate, and the amount of air supplied is regulated by a plate g, extending vertically of the box G and adjusted by the screw g'. This allows more or less air to 25 pass to the fire-box.

What I claim is—

In combination with a stove, the box G beneath the fire-box thereof, the air-supply pipe communicating with said box, the plate movable in said box to regulate the passage of air therethrough, and the screw for operating said plate, substantially as described. 30

In testimony whereof I have signed my name to this specification in the presence of 35 two subscribing witnesses.

EMILE LAROCHE.

Witnesses:

A. SARDET,

M. PELLERIER.
